UNITED STATES PATENT OFFICE.

JOSEPH ERNST FLETCHER, OF DUDLEY, ENGLAND.

STOCKLESS ANCHOR.

Application filed August 8, 1924. Serial No. 730,963.

To all whom it may concern:

Be it known that I, JOSEPH ERNST FLETCHER, a subject of the King of England, and residing at Dudley, in the county of Stafford, England, have invented Improvements in Stockless Anchors, of which the following is a specification.

This invention has reference to anchors of the "stockless" or "patent" type, namely, 10 the type in which the arms or flukes are pivoted, and adapted to move about a pivot or axis lying in the general plane of the anchor, and the shank of the anchor carries or is attached to the pivot; and it relates 15 more especially to anchors of the kind the head and flukes of which are of cast steel or iron.

To obtain sufficient strength in the anchor head and arms of an anchor of convenient 20 overall dimensions, and to provide ample weight, the bulk of the weight of the head is usually placed in the neighbourhood of the axis or pivot, and this has necessitated the 25 making of the anchor head casting of such design as is likely to introduce internal stresses, cavities, shrink holes, and hidden flaws within the steel, especially in the neighbourhood of the heavy sections surrounding the pivot pin, or pins or trunnions and at 30 the arm ends adjacent to the same.

Differential contractions, as is well known, take place in any steel casting having varying thicknesses of section in contiguous areas and such differential contraction leads to 35 "pulls" or cracks at the points or positions where, during solidification from the molten state, one part is freezing rapidly whilst an adjacent part may still be molten; and it is the primary object and effect of this 40 invention to obviate or avoid defects and drawbacks of these kinds in an anchor of the character or construction specified.

In an anchor according to this invention, the head casting, which is in usual practice 45 designed so as to weigh say more than half of the total weight of the anchor, is proportioned as regards the thickness of the metal generally, so that there is no excess thickness in the neighbourhood of the trunnions and arm ends. This casting may weigh, say, less than half of the total anchor weight, and though having the same over-all dimensions of a normal anchor, will be 50 stronger than the usual form, and be possessed of greater elasticity and ability to resist shock or impulsive stresses; and it is

cast with cavities or recesses in the arm ends or crown, and the requisite full weight required, is attained by means of metal blocks, preferably cast iron or so called semi-steel 60 blocks, which are fitted within the crown of the head or arm ends, and held in position by the pivot or trunnion pin or shaft, which may pass across the entire width of the anchor head, or be secured by suitable cross 65 pins or bolts passing through the head at the back of the trunnion pin, and at right angles to such pin, or in any other suitable manner.

The parts of the crown or arm ends in 70 which the cavities are formed, are so formed, that the cast iron or semi-steel weighting blocks, firmly secured within the anchor head, or crown, will be protected by the construction of same, that they will not be subjected to stress, and possibility of fracture, 75 in case the anchor should fall violently on its head, and strike the bottom, is prevented.

The weighting blocks and parts are in 80 some cases so constructed and arranged that they provide a means for elastically taking up the pull on the shank, and trunnion pin or shaft when the anchor is functioning normally, and especially when subjected to 85 impulsive stresses through the cable; and the blocks may be split, say at the outer part, and grip the trunnion pin or shaft; and the sides of the cavities in the crown or arm ends, in which the blocks lie, may be inclined converging together at the bottom, 90 while the outer parts or ends of the cavity walls extend over inwards towards each other, and in the portions of the cavity so formed, the ends of the blocks may fit and be held. 95

The anchor according to this invention, the nature of which is above described, is illustrated in the accompanying drawings, in which Figure 1 is a general view of the anchor, Figure 2 is an end view, Figure 3 100 is an end view in cross section, and Figure 4 is a plan. Figure 5 is a modification.

Referring to the drawings, 1 designates the head portion generally, which as stated is usually in practice designed so as to weigh 105 say more than half of the total weight of the anchor, which is very often several tons. 2 are the trunnions, 3 the shank, and 4 the rams or flukes.

In the portions of the head from which 110 the arms or flukes 4 extend, the large cavities or chambers 5 are cast, so that the metal

round these cavities or chambers is comparatively thin as shown; and the cavities extend from the ends inwards, to the degree as shown, so that a wall of metal of suitable thickness remains between the ends thereof, and the hole 9 in the head through which the head of the shank 3 passes, and in which it lies and works.

The requisite full weight required in the 10 anchor head is attained by the cast metal blocks 6, say cast iron blocks, which are introduced into and practically fill the cavities or chambers 5 of the head; and they are held in position in the case shown by cross 15 rivets 7, but other suitable holding or retaining means may be employed.

In the construction of anchor shown, the 20 portions of the head, from which the upper ends of the arm 4 extend, are shown convex at their upper part, and from the 25 edges of this part, the contour of the head is in the form of downwardly inclined portions, the lower parts of which merge into the roots or upper parts of the arms or 30 flukes; and from other portions of these upper edges of the convex parts, the trippers 8 extend. Thus, the end portions of the head are a species of triangular form, and the cavities 5 are correspondingly made, as 35 are also of course the blocks 6, which fill them.

By the construction shown, the weighting 35 blocks 6 are protected, so that they do not become subjected to stress, and the possibility of fracture, in case the anchor should fall violently on its head in striking the bottom.

The central portion of the anchor head is 40 provided with a hole 9 as stated, through 45 which the shank 3 is passed; and holes are provided in its side walls, between the inner ends of the cavities 5 and the hole 9, through 50 which the trunnion pin 2 of the shank is passed when connecting the shank to the head; and when in position in the head, it 55 will be held and locked in this position by the presence of the blocks 6.

When the anchor head strikes the bottom, 55 the thrust of the shank on the anchor through the trunnions 2 is thus taken directly by the cast metal of the head, namely, that of the side walls of the hole 9; and the sides of the shank head being close to the walls, only a direct shearing strain comes on the trunnion.

The gripping and holding power of an 60 anchor of the "stockless" or so-called "patent" type, though largely dependent on the overall dimensions of the head and shank, such as the distance between the flukes and the size and shape of same; the length of the arms, width and depth of trippers; the angle of cant and the length of the shank, is also dependent on its total weight, and 65 on the disposition of the metal masses on

the two sides of the trunnion or axis about which the head and arms oscillate relatively to the shank. These powers are preserved or attained in this anchor, viz, by having as far as possible uniform thickness of metal 70 on its several parts and constructed as described, and it possesses the advantages and qualities above specified.

The casting is proportioned, as regards the thickness of the metal generally, so that 75 there is no excess of thickness in the neighbourhood of the trunnion, the arm or fluke upper ends, or other parts.

Figure 5 of the drawings shows the modification wherein the weighting blocks are 80 constructed and arranged so as to provide a means for elastically taking up the pull on the shank, and the trunnion pin, when the anchor is functioning normally, and especially when subjected to impulsive stress 85 through the cable.

In the construction shown, by which these effects are accomplished, the blocks 6 are split at the top at the point 10, whilst the trunnion pin will extend on either side 90 through the two blocks, and may be secured at the outside ends by rings or nuts and cotter pins or like fastenings; and the blocks would be constructed so that the metal forming the inside surface of the holes of 95 the blocks 6 would grip the extended ends of the trunnion.

In the case shown, the blocks 6—which should be of steel—are of the general formation of those shown in Figures 1 to 4; 100 but their two upper outer angles 6^x are adapted to fit in and make contact with the interior angles of the chambers 5 in the ends of the head 1 in which the blocks lie as seen in the figure; whilst the parts of the 105 block which are beneath this point 6^x may be out of contact with the angular interior surface of the hole or cavity 5, and the trunnion may be loose in the holes in the walls between the shank hole 9 and the end of the 110 chambers 5.

In this case furthermore, the roof of the chambers 5 is partly open as shown.

Having now particularly described and ascertained the nature of my invention, and 115 in what manner the same is to be performed, I declare that what I claim is;—

1. A cast anchor, having the head portion in line with the flukes formed with cavities wholly closed except through an opening at 120 the end of the head, and metal blocks secured within said cavities.

2. A cast metal anchor having the central portion of its head formed with a shank opening, and the end portions of the head 125 formed with cavities opening through the ends, said cavities being otherwise closed and terminating short of the shank opening, blocks removably secured in said cavities, and a shank pivot pin supported in the 130

walls of the shank opening and extending through said walls and into said cavities.

3. A cast metal anchor having a head, flukes extending therefrom, said head being formed with cavities in line with the flukes, and weighting blocks arranged in said cavities as independent elements, a shank movably mounted in the head, the weighting blocks receiving the pivot of the shank and being longitudinally divided to provide a

means for elastically taking up the pull on the shank.

In testimony whereof I have signed my name to this specification in the presence of two subscribing witnesses.

JOSEPH ERNST FLETCHER.
